CLARENCE P. COOK, OF WATERBURY, CONNECTICUT, ASSIGNOR TO SCOVILL MANUFACTURING COMPANY, OF WATERBURY, CONNECTICUT, A CORPORATION OF CONNECTICUT

SPRINKLER TOP FOR CONTAINERS

Application filed October 20, 1927. Serial No. 227,379.

This invention relates to certain improvements in sprinkler tops for bottles for perfume and the like.

In dispensing certain liquid materials, as perfume, it is desirable that a top should be provided for the perfume container, usually a bottle, by which a small amount of perfume, as a drop, may be dispensed, and certain sprinkler top constructions have been devised for doing this. It is desirable under some circumstances, however, that the whole closure for the bottle should be readily removable so that a larger amount of the liquid material may be dispensed where desired.

It is the particular object of the present invention to provide a closure for such bottles or the like which includes a cork and a sprinkler top so associated with the cork that the cork and top as a whole may be removed from the bottle, or the sprinkler top may be operated to dispense liquid from the bottle without removing the cork.

A further object of the invention is to produce such a construction which can be cheaply made and of few parts so that the closure can be readily assembled, and which may be replaced and removed as a whole from the bottle or other container.

With these and other objects not specifically referred to in view, the invention consists in certain novel parts, arrangements and combinations which will be described in connection with the accompanying drawings and the novel features pointed out in the claim hereunto annexed.

In these drawings—

Figure 1 is a side elevation of a bottle showing the closure in place;

Figure 2 is a sectional view of the closure, the parts being shown in closed position;

Figure 3 is a similar view showing the parts in open or sprinkler position;

Figure 4 is a modified form of closure which may be employed under some circumstances, and

Figure 5 is a sectional view of the construction shown in Figure 4.

Referring now to these drawings, a container 1, shown in the form of a conventional bottle, is closed by the closure indicated gen-

erally by the numeral 2. This closure will include a cork 3 and a sprinkler mechanism by which a small amount of liquid may be dispensed from the bottle. While this sprinkler mechanism may be varied widely in construction, a convenient one is that shown in which the cork is provided with a large recess 4 and a smaller recess 5 opening into the recess 4, the recess 4 opening through the top of the cork. Mounted to move in this recess is a plug 6 having side channels, one of which is indicated at 7, this plug terminating in an outer knob 8, by which the plug may be manipulated for dispensing purposes. The lower end of the plug is formed with a solid projection 9, which normally extends through and closes the recess 5 in the cork. The lower end of the plug is formed with a skirt 10 which limits the movement of the plug as hereinafter referred to.

The plug is held in position by a cap 11, which has a central upwardly projecting flange or neck 12 forming a seat for a flange 13 formed on the upper end of the plug. The flange 10 is of greater diameter than the neck 12, so that when the plug is withdrawn to the position shown in Figure 3 the flange engages the under side of the neck and prevents further outward movement of the plug. This movement of the plug, however, withdraws the projection 9 from the recess 5 and permits excess of liquid to the recess 4, from which it escapes through the channel 7 when the parts are in the position shown in Figure 3.

The cap is associated with the cork so that the cork, cap, and plunger may be withdrawn as a whole from the bottle, and the means employed for so associating the parts are such as not to weaken the cork. As shown, referring first to Figure 2, the cap is provided with a skirt 14 which extends down over the top edge of the cork and engages the side walls of the cork for a considerable distance below the top. In associating the parts, the lower edge of this skirt is bent or spun into engagement with the walls of the cork, the cork being compressed at that point, as shown at 15 in Figures 2 and 3. This skirt 14 ex-

tends peripherally around the cork, so that a very snug engagement of the skirt and cork is effected without in any way weakening the cork, and the cork and sprinkler mechanisms may be removed as a whole from the bottle.

If desired, the construction shown in Figure 4 may be employed instead of that shown in Figure 2. In this construction the edge of the skirt 14 is slightly crimped, as indicated at 16, and pressed into engagement with the side walls of the cork, as indicated in Figure 5. This construction also provides a firm engagement between the cap and the cork, so that the cork and cap may be removed as a whole from the bottle when it is desired to have a full pouring opening.

While the invention has been shown and described in its preferred forms, it will be understood that various changes may be made in the shape and character of the container and in the sprinkler mechanism shown without departing from the invention as defined in the appended claim.

What I claim is:

- 25 In a dispensing device of the character described, a bottle or the like and a stopper therefor, said stopper being of cork or like material, and having associated therewith a sprinkler device by which a relatively small amount of the liquid contents of the bottle may be distributed through the cork when in position on the bottle, means for securing the sprinkler device to the cork, said cork and associated sprinkler device being freely removable from the bottle and replaceable thereon as a whole without injury to the cork, so that a relatively large amount of the liquid contents of the bottle can be distributed through the bottle neck.
- 40 In testimony whereof, I have hereunto set my hand.

CLARENCE P. COOK.
